UNITED STATES PATENT OFFICE

ROBERT R. McCOY, OF CUMBERLAND, MARYLAND, ASSIGNOR TO WHITE AND HAINES
OPTICAL CO., OF COLUMBUS, OHIO, A CORPORATION OF OHIO

DESIGN FOR AN OPHTHALMIC MOUNTING

Application filed May 18, 1929. Serial No. 31,288. Term of patent 14 years.

To all whom it may concern:

Be it known that ROBERT R. McCoy, a citizen in the United States, residing at Cumberland, of the county of Allegany and State of Maryland, has invented a certain new, original, and ornamental Design for an Ophthalmic Mounting, of which the following is a specification, reference being had to the accompanying drawings, forming a part thereof.

The figure is a front perspective view of an ophthalmic mounting embodying my new design.

I claim:

The ornamental design for an ophthalmic mounting substantially as shown.

In testimony whereof I affix my signature.

ROBERT R. McCOY.
